UNITED STATES PATENT OFFICE.

ISAAC S. DEMENT, OF EAST ORANGE, NEW JERSEY, ASSIGNOR TO AMERICAN MECHANICAL CASHIER COMPANY, OF NEW YORK, N. Y., A CORPORATION OF NEW YORK.

REGISTER.

No. 818,235.

Specification of Letters Patent.

Patented April 17, 1906.

Application filed July 28, 1903. Renewed December 7, 1905. Serial No. 290,752.

To all whom it may concern:

Be it known that I, ISAAC S. DEMENT, a citizen of the United States, residing at East Orange, in the county of Essex and State of New Jersey, have invented certain new and useful Improvements in Registers, of which the following is a specification.

This invention relates to improvements in registers; and one of its objects is to provide for accumulating from lower to higher denominations by means of operating devices controlling the register-shafts, so that there will be a positive progression with the least possible friction and uncertainty of operation.

15 A further object of the invention is to provide means for resetting the register-shafts to zero after they have been operated for a given period of time or when it is so desired.

In the accompanying drawings, Figure 1 is 20 a plan view of a portion of the keyboard and register embodying the invention, the keys and certain of the other parts being omitted. Fig. 2 is a partial similar view, on an enlarged scale; but in this the parts are broken away 25 for convenience of showing other parts which would be hidden thereby. Figs. 3 and 4 show in transverse sectional elevation and in normal and shifted position, respectively, the register dials operating mechanism and parts

30 of its controlling mechanism. Fig. 5 is a top view of the register-dials, shafts, and "carrying" mechanism. Fig. 6 is a sectional elevation in the plane indicated by the line 6 6 of Fig. 1 of the same mechanism; and Fig. 7 is a 35 similar view on the line 7 7 of Fig. 1, the view being taken in the opposite direction from Fig. 6. Fig. 8 is a horizontal sectional view of the register-dials and a portion of the means for resetting the same to zero. Fig. 9

40 is a vertical sectional elevation of the means for resetting to zero. Fig. 10 is a face view of a portion of the machine, showing the arrangement of the register-dials. Fig. 11 is an elevation of the dial-shaft-actuating 45 ratchet-wheel and contiguous mechanism. Fig. 12 is a side view of the actuating-cam of the carrying mechanism. Figs. 13, 14, and 15 are detail views of the resetting mechanism for the carrying devices.

50 A stationary frame for the movable parts of the machine is indicated at 1. On the dials 2 are arranged the numerals for the registration of purchases made in any desired

system of coinage. For example, in the present instance and referring to Fig. 10, the 55 dial at the extreme right hand may represent farthings, counting from "1" to "3." The next dial to the left may represent pence, counting the same from "1" to "11." The next two dials may represent the units and 60 tens of shillings, and the three dials to the extreme left may represent units, tens, and hundreds of pounds. In each instance the indicating-figure showing the temporary total of amounts are shown through holes 3 in the 65 face of the machine. These dials are mounted upon shafts 4, (see Figs. 1 and 8,) which are driven by pinions 5. With these pinions the teeth on the under side of controller rack-bars 6 engage. Each pinion 5 has attached to it a ratchet-wheel 7, and the two wheels revolve freely upon the shafts 4 between 70 wheels or collars 8 9. Upon collar 9, however, is a pawl 10, (see Figs. 5 and 11,) spring-pressed against the ratchet-wheel 7 by a 75 spring 11. The result of this construction is that when the bar 6 is thrown outward—that is, in the direction of the arrow in Fig. 1—it turns the pinion 5, and the ratchet-wheel 7 will run freely under the pawl 10; but when 80 the bar 6 is pressed backward in a direction contrary to the arrow of Fig. 1 the pawl 10, engaging the ratchet-wheel 7, is rotated by the same, carrying with it the collar 9, which being fixed to shaft 4 rotates the latter and 85 with it its registering-dial 2. In the present drawings there are indicated merely the stop-plates 12, whose lugs 13 are moved into the path of the shoulders upon bars 6 when the oscillating yokes 14 are oscillated by the keyboard-keys. (Not shown.) These yokes 14 engage teeth 15 on the stop-plates 12, so that when a yoke is oscillated the stop-plate which it engages is forced in a line transverse to the bars 6, bringing its lug 13 (see Fig. 2) across 90 the line of motion of the shoulder 16 of bars 6.

The bar 6 is held in normal position by means of an oscillating lock-plate 17, which has a lip 18 engaging the shoulder 16, and the lock 17 is oscillated by the lug 13 to free the 100 shoulder 16 from the lip 18 when it enters the guide-groove 19 of bar 6, as shown in Fig. 2. When so released, the bar 6 springs out—that is, in the direction of the arrow, Fig. 1—until its shoulder 16 abuts against the lug 13 105 on stop-plate 12, and the extent of its move-

ment will depend, therefore, upon which one of the stop-plates 12 has been operated; and therefore upon which one of the yokes 14 has been operated by its corresponding key. By referring to Fig. 1 it will be noticed that each stop-plate 12 is provided with a tooth 15, which is adapted to be engaged by one of the oscillating yokes 14. Thus when a yoke is oscillated by one of the keyboard-keys, it will engage the stop-plate tooth 15 and move said stop-plate forward to operatively control a bar 6. The movement of any one of the stop-plates 12 is determined by a yoke 14, the yokes from right to left being controlled by the keyboard-keys from "0" to "9." The extent of projection of the bar 6 will determine the extent of its return motion, and therefore the extent of rotation of the register-dial 2. The return motion of the bar 6 to the normal position shown in Fig. 1 is effected by cams, which engage the outer ends 20 of said bar. Such cams are here shown in dotted lines at 30, Fig. 7, and are arranged to successively engage the rack-bars 6 from 25 lowest to highest denomination when said rack-bars are being reset to control the register shafts and dials. The extent of the return motion of the bars 6 to normal is determined by shoulders 21 thereon engaging a 30 shoulder 22. When these two shoulders have come into engagement in the normal operation of the machine, as shown at the bottom of Fig. 2, the bar 6 is at rest, and it will be held from being again projected forward by the reengagement of the lip 18 of lock 17 behind the shoulder 16. The propelling force of the bars 6 outward is a spring 23, (indicated in detail in Fig. 3,) which is fastened at one end by a bar 6 and at the 35 other end to a stationary part of the machine-frame. A spring 24 also acts to cause the engagement of lock 17 18 with the shoulder 16. The outer end of the bar 6 has a hinged member 25, which is held to vertical position by a spring 26 of sufficient strength to resist any 40 tendency of the face-piece 25 to turn about its pivot 27 when the rack-bar is forced in by its operating-cam. When, however, the shoulder 21 on the rack-bar engages the shoulder 22 on the stop 28, the spring 26 will yield, allowing the face-piece 25 to turn upon its pivot 27 and allow the cam to move from engagement therewith. Should, however, the stop 28 be shifted so that the shoulder 22 45 is no longer in line with the shoulder 21, as shown in the second bar from the bottom of Fig. 2, the face-piece 25 being held by its spring 26, still in engagement with the operating-cam, the rack-bar will on the continuation of rotation of the cam be forced another 50 step farther in until it engages the second shoulder 29 on stop 28. Thus the bar 6 can be given at times a motion equivalent to the distance between the two shoulders 22 29 in 55 addition to the normal motion provided for

by the outward projection of the bar. This extra motion, which is equivalent to the turning of the register-dial from one figure to the next following one, is given in the "carrying," operation—that is to say, when one dial has counted up to a number one less than the amount indicated by a single unit on the next dial the next following operation of the lower dial will cause the setting of mechanism causing a single step forward of the upper dial. Suppose, for example, the right-hand dial of Fig. 10, which is intended for counting farthings, indicates "3," its next forward step should set mechanism which will cause the rotation of the second dial at a single unit. To effect this operation, it is necessary to shift the stop-plate 28, as already described, and for this purpose there are provided upon the dial-shafts 4 cam-wheels 8, having cams or teeth 31, one or more in number, depending on the number of duplications of the unit of measurement there are upon the dial. For example, suppose there be three sets of figures from "1" to "3" on the farthings-dial, there would be three cam-teeth 31 upon the cam-wheel 8, so that each time the dial moves from "3" to "1" its tooth 31 will cause the operation of the carrying mechanism. The tooth 31 is arranged to strike an arm 32, projecting from a rock-shaft 33, to which the stop plate or piece 28 is fixed (see Fig. 6) by its arms 34. The spring 35, fastened at one end to one of the arms 34 of stop-piece 28 and at its other end to a stationary part of the machine-frame, tends to hold and return stop-piece 28 into the position shown at the bottom of Fig. 2—that is to say, the position in which the shoulders 21 and 22 engage.

36 represents dogs pivoted upon the stop-pieces 28 at 37 and dropping under the combined influence of gravity and springs 38 behind shoulders 39 on a stationary stop-plate 40 when the stop-piece 28 is rocked by one of the cam-teeth 31. This combination is exhibited on the bar next above the bottom in Fig. 2—that is to say, the stop-piece 28 has been rocked so that its shoulder 22 no longer engages the shoulder 21, this condition being caused by the corresponding cam-tooth 31 115 engaging the arm 32 of the rock-shaft 33 of stop-piece 28. The extent to which the dog 36 will fall is limited by a stop-pin 41, which engages the flat surface of stationary stop-plate 40. In this position of the parts when the bar 6 is forced in by its operating-cam its shoulder 21 will not be stopped by engagement with the shoulder 22, but will pass on into engagement with the shoulder 29, and thus the additional counting-step is made on the register. It is, of course, understood that the stop-piece 28 of any bar is operated by the cam-tooth 31 of the next lower register dial-shaft.

When the bar 6 is forced in to effect the 130

carrying operation, an inclined surface 42 thereon engages an inclined tooth 43 of dog 36, lifting the latter so that its projecting end 44 no longer engages the shoulder of stationary stop-plate 40, and therefore the spring 35 of the stop-piece 28 can turn the latter to its normal position.

This machine belongs to the class in which the operation of the key causes the setting of mechanism in such position that by the operation of a handle or lever the registering-wheels are turned to count and show the total of the transactions. The depression of a key oscillating a yoke 14 causes, as already explained, the projection of a corresponding bar 6. The rotation of the operating-handle (not shown) by rotating cams 30 then causes all bars 6 which have been projected to be thrown in, counting up the result on the dials 2 and carrying from one dial-shaft to the next higher any sum in excess of the amount counted by a lower dial.

At stated periods—as, for example, at the end of a day—it is convenient to set all the dials to zero. To quickly perform this, there is employed in this machine a handle or bar 45, carried by a short shaft 46, on which is a gear-wheel 47, engaging a sliding rack-bar 48, having rack-teeth both on top and bottom. The upper rack-teeth engage the gear-wheel 47, while the lower engage a series of pinions 49, which are loose upon the dial-shafts 4, and each of which has a bevel-edged spring-actuated pin 50.

Keyed or otherwise fixed to each shaft 4 is a wheel or block 51, chambered to receive a spring-pin 52, whose conical head 53 engages when the dial indicates zero a correspondingly-shaped seat 54 in a part of the frame 1. When by the action of the mechanism already described the dial-shaft is turned from zero position to indicate any figure counted by the machine, the conical head 53 rides out of the seat 54 and the pin 52 is projected at its other end into the path of the spring-actuated pin 50. Thus when to reset the dials to zero the handle 45 is turned, operating pinions 49, the pins 40 are all brought against any pins 52 that are projecting, and all corresponding dials are returned to zero. When a register-shaft makes more than one revolution, the pin 50 is removed from the path of pin 52 by pin 52 engaging the bevel edge of pin 50 and forcing it back into its seat. It will be observed that during this operation of resetting to zero the shafts 4, being turned forward and causing the cam-wheels 30 to revolve, may oscillate the stop-plates 28, and if the several dogs 36 should be allowed to drop such oscillated stop-plates would be held in position to start the next following operation of the machine with a carrying operation. To prevent this, the dogs 36 are held from engagement with stationary stop-plate 40 during this operation

of resetting to zero. Referring to Figs. 13, 14, and 15, it will be seen that on shaft 46 is a cam-disk 55, having a single depression 56. On the cam-disk rides a pin or roller 57 of an arm 58, being pressed to engagement by a spring 59. The arm 58 is attached to shaft 60, which has also rigid with it a series of arms 61, one for the heel 62 of each dog 36. When to reset the dials to zero the handle 45 is turned, the pin 57 rides out of depression 56 of cam-disk 55, forcing down arms 61 on the heels of dogs 36 and lifting said dogs, as shown in Fig. 15, so that their projecting ends 44 will not engage stop-plate 40.

Anchor-wheels and dogs for the several shafts 4 are indicated at 62 63.

Having thus described my invention, the following is what I claim as new therein and desire to secure by Letters Patent:

1. The combination of a plurality of register-shafts of different denominational value, a plurality of controller-bars operatively connected to the register-shafts, means for operating the controller-bars, devices projected in the path of the controller-bars to determine the return movement of the same, and means for operating said devices and register-shafts to turn a register-shaft of higher value when the lower one passes the zero-point.

2. The combination of a plurality of register-shafts of different denominational value, a plurality of controller-bars operatively connected to the register-shafts, means for operating the controller-bars, stop-plates in the path of the controller-bars to determine the return movement of the same, and means for operating said stop-plates and register-shafts to turn a register-shaft of higher value when the lower one passes the zero-point.

3. The combination of a plurality of register-shafts of different denominational value, a plurality of controller-bars operatively connected to the register-shafts, means for operating the controller-bars, oscillating stop-plates in the path of the controller-bars to determine the return movement of the same, and means for operating said oscillating stop-plates and register-shafts to turn a register-shaft of higher value when the lower one passes the zero-point.

4. The combination of a plurality of register-shafts, a plurality of controller rack-bars operatively connected to the register-shafts, means for operating said controller-bars, two shouldered oscillating stop-plates, shoulders on the bars engaging the stop-plates to determine the limit of their return movement, and means on the register-shafts operating the stop-plates to permit the turning of a register-shaft of higher value when the lower one passes the zero-point.

5. The combination of a plurality of register-shafts, a plurality of rack-bar controllers operatively connected to the register-shafts,

two shouldered oscillating stop-plates engaging shoulders on the controller-bars, cams on the register-shafts, rock-shafts supporting the stop-plates, and arms on said shafts operated upon by the cams to oscillate the stop-plates to determine the movement of the register-shaft of higher value if the lower one passes the zero-point.

6. The combination of a plurality of register-shafts, a plurality of controller rack-bars operatively connected to the register-shafts, rock-shafts supporting the oscillating stop-plates, cams on the register-shafts engaging arms on the rock-shafts to operate the oscillating stop-plates, a stationary notched stop-plate, dogs pivoted to the oscillating stop-plates and adapted to engage the notched stop-plate and retain the oscillating stop-plates in position to allow the controller rack-bars to affect the register-shafts of higher value.

7. The combination of a plurality of register-shafts, a plurality of spring-actuated controller rack-bars operatively connected thereto, means for determining the movement of the controller-bars when released, means for returning them to their initial position, cam-controlled oscillating stop-plates, dogging means for retaining them in their cam-operated positions, and shoulders on the oscillating stop-plates engaging shoulders on the controller-bars to determine the movement of the register-shaft of higher value if the lower one passes the zero-point.

8. The combination of a plurality of register-shafts, a plurality of controller rack-bars, two shouldered oscillating stop-plates mounted on rock-shafts and adapted to limit the return movement of the controller-bars, cams on the register-shafts oscillating the stop-plates during each revolution of the register-shafts to affect the oscillating stop-plate and the controller-bar of the next higher denomination.

9. The combination of a plurality of register-shafts, a plurality of controller rack-bars, cam-controlled oscillating stop-plates, a stationary stop-plate, dogging means carried by the oscillating stop-plate and adapted to engage the stationary stop-plate to permit the controller-bars to affect, in their return movement, the register-shaft of higher value when the lower one passes the zero-point.

10. The combination of a plurality of register-shafts, a plurality of controller-bars, oscillating stop-plates engaging the controller-bars, dogging means pivoted on the oscillating stop-plates, a stationary stop-plate engaged by the dogging means to hold the oscillating stop-plates in operative position, and a tooth on the dogging means engaging an inclined shoulder on the controller-bar to release the dogging means from the stationary stop-plate when the controller-bar is returned to its normal position.

11. The combination of a plurality of controller-bars, a plurality of register-shafts operated thereby, oscillating stop-plates, dogs on said plates, a stationary stop-plate engaged by said dogs, means for resetting the register-shafts to zero comprising a gear-operated rack, pinions loosely mounted on the register-shafts and engaging the rack, wheels fixed to the register-shafts, means for engaging the pinions and wheels, and means for preventing the dogs on the oscillating stop-plates from engaging the stationary stop-plate during the resetting operation.

12. The combination of a plurality of register-shafts, means for resetting the register-shafts to zero, comprising a gear-operated rack, pinions loosely mounted on the register-shafts and engaging the rack, wheels fixed to the register-shafts and carrying spring-actuated pins, and projections on the pinions adapted to engage the wheel-pins whereby the shafts will be returned to zero when the rack is operated.

13. The combination of a plurality of controller-bars, a plurality of register-shafts operated thereby, oscillating stop-plates, dogs on said stop-plates, a stationary stop-plate engaged by the dogs, a spring-actuated rock-shaft operated by the reset means, arms on said rock-shaft engaging heels on the dogs to hold them out of engagement with the stationary stop-plate during the resetting operation.

14. The combination of a plurality of register-shafts, means for resetting the register-shafts comprising a gear, a rack operated thereby, pinions loosely mounted on the register-shafts and engaging the rack, wheels fixed to the register-shafts, means for engaging the pinions and wheels, a spring-actuated rock-shaft, and a cam on the gear operating said rock-shaft, for the purposes explained.

15. The combination of a plurality of register-shafts, means for resetting the register-shafts to zero comprising a reset-shaft mounted in the frame, a gear on said shaft, a rack engaged by the gear, pinions on the register-shafts engaged by the rack, a cam on the reset-shaft, and a rock-shaft operated by said cam for the purposes explained.

16. The combination of a plurality of controller-bars, a plurality of register-shafts operated thereby, oscillating stop-plates, dogs on said stop-plates, a stationary stop-plate engaged by the dog, means for resetting the register-shafts to zero, and means for holding the dogs out of engagement with the stationary stop-plate when the register-shafts are reset to zero.

17. The combination of a plurality of registering devices and a resetting device, the said devices provided with engaging parts consisting of yielding spring-actuated pins so arranged that in the regular registering operation the engaging parts will pass each other,

while in the resetting operation the said pins will lock and the resetting device will move the registering device to its original position.

18. The combination of a registering device and a resetting device provided with engaging parts consisting of yielding spring-actuated pins, one of said engaging pins adapted to withdraw from engagement with the

other when the resetting device has moved the registering device back to its normal position.

ISAAC S. DEMENT.
